US0D1009000S

(12) **United States Design Patent** (10) Patent No.: **US D1,009,000 S**
(45) Date of Patent: ** Dec. 26, 2023

(54) **LOUDSPEAKER**

(71) Applicant: **B&W Group Ltd**, Worthing (GB)

(72) Inventors: **Edward Goodwin**, London (GB);
Richard Hartshorn, London (GB);
Mireia Gordi Vila, London (GB);
Sebastian Ahlers, London (GB);
Andrew Furner, London (GB)

(73) Assignee: **B&W Group, Ltd**

(**) Term: **15 Years**

(21) Appl. No.: **35/513,741**

(22) Filed: **Sep. 3, 2021**

(80) **Hague Agreement Data**

Int. Filing Date: **Sep. 3, 2021**
Int. Reg. No.: **DM/218314**
Int. Reg. Date: **Sep. 3, 2021**
Int. Reg. Pub. Date: **Mar. 4, 2022**

(30) **Foreign Application Priority Data**

Mar. 5, 2021 (GB) 6122901
Mar. 5, 2021 (GB) 6122904
Mar. 5, 2021 (GB) 6122906
Mar. 5, 2021 (GB) 6122908
